(57) **CLAIM**

The ornamental design for a display screen with graphical user interface, as shown and described.

DESCRIPTION

The FIGURE is a view of a display screen with graphical user interface, showing our new design.

The dot-dash broken lines in the drawing illustrate a display screen while the even broken lines illustrate portions of the graphical user interface. No subject matter shown in any of the aforementioned styles of broken lines form part of the claimed design.

1 Claim, 1 Drawing Sheet
